UNITED STATES PATENT OFFICE.

WILLIAM J. BAKER, OF NEWPORT, KENTUCKY.

WINDOW-SCREEN.

No. 834,443.

Specification of Letters Patent.

Patented Oct. 30, 1906.

Application filed February 23, 1906. Serial No. 302,518.

To all whom it may concern:

Be it known that I, WILLIAM J. BAKER, residing at Newport, in the county of Campbell and State of Kentucky, have invented 5 certain new and useful Improvements in Window-Screens, of which the following is a specification.

My invention relates to certain new and useful improvements in window-screens, and 10 more particularly embodies an improvement on the screen shown in my Patent No. 787,181, granted April 18, 1905.

Generically, my present invention comprehends an improved device for fastening the 15 screen-wire to the screen-frame, which is readily removable for purposes of replacing the wire when worn.

With other objects in view than have heretofore been specified the invention also 20 comprises certain novel construction and combination of parts, all of which will be hereinafter fully described, pointed out in the appended claims, and illustrated in the accompanying drawings, in which—

25 Figure 1 is a perspective view of a screen embodying my invention. Fig. 2 is a detail cross-sectional perspective of one form of my invention, showing the manner of securing the screen-wire. Fig. 3 is a view of the parts 30 shown in Fig. 2, separated. Fig. 4 is a view similar to Fig. 2, showing a modified form of my invention. Fig. 5 is a detail perspective view of a portion of the screen similar to Fig. 2, showing a further modification of my invention.

35 Referring now to the accompanying drawings, in which like numerals of reference indicate like parts in all of the figures, the screen-wire is indicated by 1 and the frame 40 by 2.

The screen-frame is composed of sheet-metal members and formed in two parts, the main sheet-metal frame portion 3 comprising a flat bottom portion 3^a and parallel sides 3^b 45 and 3^c, the said side 3^b having its upper edge 3^d bent over at an angle to the side 3^b, as shown, while the side 3^c has its upper edge 3^e bent over at an angle thereto toward the opposite side 3^b, as clearly understood from the 50 drawings.

In the form of my invention shown in Fig. 2 the edges 3^d and 3^e may lie in slightly-converging planes, which are shown exaggerated in the drawings for purposes of illustration.

55 4 designates the usual stiffening-rod, which is held between the sides 3^c and 3^b and the

bottom 3^a and bent-over portion 3^c of the frame, as shown in my former patent hereinbefore referred to.

5 designates a substantially U-shaped locking member consisting of the sides 5^a and leg portions 5^b 5^b, which in practice may be made slightly diverging, as shown in Fig. 2.

The screen-wire which is clamped between the side 3^b and the upper edge 3^d of the frame 65 by the U-shaped member 5, which member 5 and the member 3 are so arranged as to interlock with each other and hold the screen securely in place, the extreme edge 3^e of the bent-over portion 3^c of the frame being so 70 arranged as to project the screen-wire in a plane parallel with or slightly beyond the side 3^c of the member 3, so as to form a watershed.

In Fig. 4 I have shown a slightly-modified 75 form of my invention in which the edge 3^c is curved to follow the outline of the rod 4, while in Fig. 5 the legs 5^b 5^b of the U-shaped securing member 5 are slightly curved in cross-section, as shown, to enable the easy 80 and quick assembling of the parts.

From practical experience I have found that by constructing the screen as herein shown and described I am enabled to manufacture the same more cheaply than the 85 screen disclosed in my patent hereinbefore referred to, and by forming the edges 3^d and 3^e as described and using the U-shaped member I am enabled to more quickly attach and detach the screen-wire for purposes 90 of renewing the same, &c.

The free edge of the portion 3^d may be curled up, as at 3^m, if desired, to form a guard.

From the foregoing description, taken in connection with the accompanying drawings, the complete construction, operation, and arrangement of parts will be readily understood by those skilled in the art to which it appertains.

What I claim is—

1. A window-screen comprising a frame 100 consisting of two sheet-metal members, one of which comprises a flat bottom portion and parallel side portions of unequal lengths, each of said side portions terminating in a 105 bent-over portion projecting toward the other side portion, a screen-wire adapted to be interlocked with said frame, and the other sheet-metal member comprising a U-shaped interlocking member for interlocking with 110 the bent-over portions of the first-mentioned frame member to clamp the screen between

such first-mentioned frame member and the U-shaped locking member, substantially as shown and described.

2. A metallic window-frame including 5 side, top and bottom portions being composed of a pair of sheet-metal strips, one of said strips having a bottom and parallel side portions, said side portions being of unequal lengths, the upper edge of each side portion 10 being bent inwardly toward the other side portion and spaced apart, the second sheet-metal strip being of substantially U shape in cross-section to interlock with the first sheet-metal strip and a screen-wire held between 15 said sheet-metal strips and interlocked thereby, substantially as shown and described.

3. In a metallic window-frame, a spring-metal frame-section having a base and parallel sides, said sides being of unequal length, 20 the upper end of one of said sides being bent inwardly at an angle thereto, the upper end of the other side being bent inwardly at an angle thereto, a locking member composed of a sheet-metal strip having a straight face 25 and a pair of bent-over edges to coöperate with the bent-over edges of the first-mentioned frame-section, and a screen-wire secured between said spring-metal frame-section and said locking member, substantially 30 as shown and described.

4. A window-screen comprising a frame consisting of two sheet-metal members, one of which comprises a flat bottom portion and parallel side portions of unequal lengths, 35 each of said side portions terminating in a bent-over portion projecting toward the other side portion, a screen-wire adapted to be interlocked with said frame, and a U-shaped interlocking member for interlocking 40 with the bent-over portions of the first-mentioned frame member to clamp the screen between such first-mentioned frame member and the U-shaped locking member, the bent-over portion of one of the side portions terminating in a curled edge, substantially as 45 shown and described.

5. A metallic window-frame including side, top and bottom portions, being composed of a pair of sheet-metal strips, one of 50 said strips having a bottom and parallel side portions, said parallel side portions being of unequal length, said side portions having inwardly-bent portions spaced apart, the second sheet-metal strip being of substantially 55 U shape in cross-section to interlock with the first sheet-metal strip between the bent-over portions thereof, a screen-wire held between said sheet-metal strips and interlocked thereby, substantially as shown and described.

6. A metallic window-frame including side, top and bottom portions being composed of a pair of sheet-metal strips, one of 60 said strips having a bottom and parallel side

portions of unequal lengths, said side portions having inwardly-bent portions spaced 65 apart, the second sheet-metal strip being of substantially U shape in cross-section to interlock with the first sheet-metal strip between the bent-over portions thereof, a screen-wire held between said sheet-metal 70 strips and interlocked thereby, and one of said sides having its bent-over portion terminating in a curled edge, substantially as shown and described.

7. In a metallic window-frame, a spring-metal frame-section having a base and parallel sides, the upper end of one of said sides being bent inwardly at an angle thereto, the upper end of the other side being bent inwardly at an angle thereto, a locking member composed of sheet-metal strips having a straight face and a pair of bent-over edges to coöperate with the bent-over edges of the first-mentioned frame-section, and a screen-wire between said spring-metal frame-section and said locking member, said bent-over edges of the sheet-metal frame-section 80 lying in converging planes, substantially as shown and described.

8. In a metallic window-frame, a spring-metal frame-section having a base and parallel sides, the upper portion of one of said sides being bent inwardly at an angle thereto, the upper portion of the other side being bent inwardly at an angle thereto, a locking member composed of sheet-metal strips having a straight face and a pair of bent-over portions to coöperate with the bent-over portions of the first-mentioned frame-section, and a screen-wire between said spring-metal frame-section and said locking member, said bent-over portions of said locking member lying in 90 diverging planes, substantially as shown and described.

9. In a metallic window-frame, a spring-metal frame-section having a base and parallel sides, the upper portion of one of said sides being bent inwardly at an angle thereto, the upper portion of the other side being bent inwardly at an angle thereto, a locking member composed of sheet-metal strips having a straight face and a pair of bent-over portions to coöperate with the bent-over portions of the first-mentioned frame-section, and a screen-wire between said spring-metal frame-section and said locking member, said bent-over portions of the sheet-metal frame-section lying in converging planes, said bent-over portions of said locking member lying in 100 diverging planes, substantially as shown and described.
